CHARLES STEPHENS, OF RICHMOND, VIRGINIA.

RAILWAY SIGNALING.

1,316,811.

Specification of Letters Patent. Patented Sept. 23, 1919.

Application filed August 2, 1916. Serial No. 112,700.

To all whom it may concern:

Be it known that I, CHARLES STEPHENS, a citizen of the United States, residing at Richmond, in the county of Henrico and 5 State of Virginia, have invented certain new and useful Improvements in Railway Signaling, of which the following is a specification.

My invention relates to railway signaling, 10 and particularly to apparatus for the control of signals governing traffic in opposite directions over a stretch of track.

I shall describe one form and arrangement 15 of apparatus and circuits embodying my invention, and will then point out the novel features thereof in claims.

In the accompanying drawing, Figure 1 is 20 a diagrammatic view showing one form and arrangement of apparatus and circuits embodying my invention: Fig. 2 is a view showing in vertical section and on an enlarged scale one of the locking devices *h* of Fig. 1.

Similar reference characters refer to similar parts in each of the several views.

Referring first to Fig. 1, reference characters 1 and 2 designate the westbound and the eastbound tracks respectively of a double track railway. A portion of track 1 between 30 points X and Y is provided with a so-called automatic block signaling system. For this signaling system stretch X—Y of track 1 is divided into block sections X—V and V—Y having signals D and E stationed adjacent the entrance ends of the sections for 35 governing westbound traffic. For the control of these signals the block sections are provided with track circuits comprising track relays *R*^a and *R*^e respectively. As 40 shown on the drawing, signals D and E are controlled by relays *R*^a and *R*^e through local signal circuits which are closed or opened by the relays to cause the signals to indicate "proceed" and "stop" respectively. At the 45 ends of stretch X—Y the track rails 1 and 2 are divided into short sections W—X and Y—Z respectively, in which sections are crossovers *C*^a and *C*^b for switching traffic from one track to the other. It is at times 50 desirable to send eastbound traffic through stretch X—Y over track 1 in opposite to normal direction, via the following route, from track 2 through crossover *C*^a, track 1 of stretch X—Y, crossover *C*^b to track 2. 55 Traffic over this route is governed by a signal A at the entrance to section W—X.

Traffic over track 1 in normal direction is governed by a signal B at the entrance to section Z—Y.

For the control of the signals A and B, 60 sections W—X and Y—Z are provided with track circuits comprising relays *R*^a and *R*^b, respectively, whose contacts govern the signal circuits as I shall describe hereinafter. For operating these signals I provide signal 65 levers *S*^a and *S*^b comprised in interlocking machines of which there is one adjacent each end of the stretch and which machines are located in so-called interlocking towers *T*^a and *T*^b. Each of the signal levers is capable 70 of two positions, a normal position designated N, corresponding to the stop indication of the signal governed by the lever, and a reversed position designated R corresponding to the proceed indication of the 75 corresponding signal. Contact segments *a* and *b* are provided on the shafts of the signal levers for the control of the signal circuits, as I shall describe hereinafter.

Located also in towers *T*^a and *T*^b respectively are levers *L*^a and *L*^b, which I shall term traffic levers to intimate that their purpose is to control the direction of traffic on track 1. Each of these levers is capable of 80 three positions, a normal position, designated N, in which traffic may be allowed to pass over track 1 in the normal direction, *i. e.* from east to west; a reversed position designated R, in which traffic may be permitted to proceed over track 1 in the reversed direction (from west to east), and a 85 central position, designated C in which no traffic can be sent over track 1 in either direction. These positions of the traffic levers are controlled by locking devices *h*. Referring also to Fig. 2, each locking device comprises a segment 4 fixed to the lever shaft 3, a latch 5 adapted to coact with a dog 6 on the segment, and a motor *M*^a to control the latch 5. When lever *L*^a is turned from its 90 normal position toward its reversed position, the lever is arrested in the central position, by the engagement of dog 6 with latch 5. To permit a completion of the stroke of the lever latch 5 must be raised until the upper 95 bar of the latch clears dog 6. The up and down movements of the latch are controlled by the motor *M*^a, through the medium of a centrifugal governor 7. As shown in Fig. 2, motor *M*^a has a hollow vertical shaft 90, 100 which rotates in bearings 91 and 92 of a frame 93, which is secured by a threaded

neck to the frame of the interlocking machine for the lever. The arms 94 of the governor are pivoted in brackets 95 secured to the shaft 90. Immediately below these 5 brackets the shaft is slotted to receive a bar 96 attached to the arms 94 by links 98. Bar 96 is drilled to receive the pointed tip of a rod 97 which is free to move in shaft 90. The latch 5 is attached to the upper end of 10 rod 97. When the motor M^a is rotated the governor fly balls spread and lift bar 96, raising thereby rod 97 a sufficient distance that the upper bar of latch 5 clears dog 6. It should here be noted that this mechanism 15 is so adjusted that the centrifugal force developed by the governor is sufficient to raise the latch only if the motor is rotating at or above a predetermined speed, as controlled by the frequency of the current supplied to the motor. Lever L^b is 20 provided with a similar locking device controlled by a motor M^b which locking device, however, functions to lock the lever against a movement from the reversed to the normal 25 position. I shall describe hereinafter the control of motors M^a and M^b for effecting at the proper time a release of the corresponding levers.

Located also in towers T^a and T^b respectively, are buzzers U^a and U^b , and drop annunciators O^a and O^b for signaling between the towers as I shall describe hereinafter. H^a and H^b are hand generators for furnishing current of the proper frequency to operate the motors M^a and M^b , buzzers U^a and U^b , and annunciators O^a and O^b , as I shall describe hereinafter. There are also located 35 a relay Q at tower T^a and relays P^a and P^b at towers T^a and T^b respectively, which relays enter into the control of the signaling circuits as I shall describe presently.

As described hereinbefore a complete stroke of lever L^a from its normal position to its reversed position is prevented by its locking device h until motor M^a is energized by current of a predetermined frequency. The circuit for energizing motor M^a is: from hand generator H^b in tower T^b , through wire 52, contact 45 of relay R^b , 40 wire 46, push button F^b , wire 47, contact segment b of lever L^b reversed, wires 48 and 39, buzzer U^b , wire 38, contact 37 of relay R^a , wire 36, contact 35 of relay R^a , wire 34, buzzer U^a , wire 33, contact b of lever L^a 45 in the center position, wire 54, motor M^a , wires 55, 44 and 51 to hand generator H^a . It follows, therefore, that a complete reverse movement of lever L^a can be effected only when lever L^b is in the reversed position. 50 Similarly, the traffic lever L^b can be returned from its reversed position to its normal position only if motor M^b is energized when the lever arrives in the center position. The circuit for energizing motor M^b is: from 55 hand generator H^a , through wire 16, con-

tact 30 of relay P^a , wire 31, push button F^a , wire 32, contact segment a of lever L^a normal, wire 33, buzzer U^a , wire 34, contact 35 of relay R^a , wire 36, contact 37 of relay R^a , wire 38, buzzer U^b , wire 39, wire 48, contact segment c of lever L^b in the center position, wire 70, motor M^b , and wires 44 and 71 to generator H^a . It follows that lever L^b can be operated to its normal position only when lever L^a is in the normal position. 75 Since it is also true that traffic lever L^a can be reversed only when traffic lever L^b is reversed, it follows that it is never possible to have simultaneously a reverse position of lever L^a and a normal position of lever L^b . 80

The circuits traced above for the control of motors M^a and M^b , show that each motor can be energized only by the hand generator located at the other tower, H^b or H^a , respectively. However, to prevent an energization of either motor when by an accidental cross of wires the adjacent hand generator is connected into the adjacent motor circuit, the generator fields are controlled in the following manner. The field 10 of generator H^a is controlled by the circuit: from battery K^a , through wire 11, field 10 of generator H^a , wire 12, push button F^a , wire 13, contact segment e of traffic lever L^a in the normal position, and wire 15 to battery K^a . 95 In the above circuit the contact segment e of levers L^a is provided with a shunt comprising contact segment f of the same lever, which segment is closed when the lever is in the reversed position. The circuit for field 10 is closed therefore when push button F^a is depressed and lever L^a is in either its normal or reversed positions, but not when this lever is in the center position. Consequently, when lever L^a is turned to its 100 center position (in order to close the circuit for motor M^a), the circuit for field 10 of generator H^a is open, so that current cannot be obtained from this generator, thus making it impossible to receive a false energization of motor M^a . The control for the circuit of field 10 of generator H^b is similar to the circuit described above for the control of the field 10 of generator H^a .

The traffic levers control the adjacent signal levers, preferably by mechanical interlocking. This control (which I have indicated by legends on the drawings) is such that signal lever S^a can be reversed only when traffic lever L^a is in the reversed position, whereas signal lever S^b can be reversed only when traffic lever L^b is in the normal position. I have shown hereinbefore that because of locking devices h it is impossible to get, simultaneously, the reversed position 120 of lever L^a and the normal position of lever L^b . It follows, therefore, that both of the signal levers cannot be in their reversed positions at one time.

A reverse movement of signal lever S^a 130

operates signal A to the proceed indication by closure of the following circuit: from battery B^a, through wires 17 and 62, contact 63 of relay Q, wire 64, contact segment b of signal lever S^a reversed, wire 65, operating mechanism of signal A and wire 66 to battery B^a. Similarly, a reverse movement of signal lever S^b operates signal B to the proceed indication by closing the circuit: 10 from battery B^b, through wire 78, contact segment d of traffic lever L^b normal, wire 79, contact segment b of signal lever S^b reversed, wire 80, contact 81 of relay P^b, wire 82, operating mechanism of signal B 15 and wire 83 to battery B^b. In view of the fact that the two signal levers cannot be in the reversed positions simultaneously, it is now apparent that the signals A and B cannot indicate "proceed" at one time. Thus 20 two cars or trains can never secure permission at the same time to pass over track 1 in opposite directions.

The circuit traced above for signal A is controlled not only by lever S^a but also by 25 contact 63 of relay Q, and it is apparent that signal A can be operated to and retained in the proceed position by signal lever S^a only while relay Q is energized. The energizing circuit for relay Q is: from battery B^a, 30 through wires 17 and 56, contact 57 of relay P^a, wire 58, contact segment d of traffic lever L^a reversed, wire 59, relay Q, wires 60 and 66 to battery B^a. Relay Q, therefore, is closed only when relay P^a is energized 35 and traffic lever L^a is reversed, so that it is apparent that a proceed indication of signal A can be given and maintained only while traffic lever L^a is reversed and relay P^a is energized.

40 Relay P^a has two circuits, a pick-up circuit and a holding circuit. The former circuit comprises the following connections: from battery B^a, through wire 17, contact 18 of relay R^a, wire 20, relay P^a, wire 21, 45 contact segment c of traffic lever L^a normal, wire 22, contact segment a of signal lever S^a normal, and wire 23 to battery B^a. This circuit can be closed to pick up relay P^a only if levers L^a and S^a are normal, provided 50 however that section W—X of track 1 is unoccupied by a car or train. The holding circuit for this relay is the same as the pick-up circuit up to and including relay P^a, then through contact finger 73, wires 74 and 66 55 to battery B^a. This circuit is independent of the control of levers L^a and S^a so that relay P^a after it has been picked up remains closed, regardless of the positions of these levers, until relay R^a is deenergized by the 60 entrance of a car or train into section W—X.

From the above described circuits, it follows that signal A can be operated to its proceed position only by first throwing levers L^a and S^a to their normal positions to pick 65 up relay P^a, then reversing lever L^a to ener-

gize relay Q and finally reversing lever S^a to close the signal circuit. The presence of a train in section W—X, however, makes it impossible either to effect or to retain the proceed indication of signal A.

70

Signal B is controlled by relay P^b, traffic lever L^b and signal lever S^b, as pointed out in a previous description of the circuit for this signal. For closure of this circuit lever L^b must be at normal and relay P^b 75 must be energized when the signal lever S^b is operated to its reversed position. The relay P^b, similar to relay P^a of tower T^a, has a pick-up and a holding circuit. The former circuit is as follows: from battery B^b, 80 through wire 73, contact 28 of relay R^b, wire 27, contact segment g of lever L^b, wire 26, relay P^b, wire 25, contact segment a of lever S^b and wire 24 to battery B^b. Relay P^b can, therefore, be energized by throwing 85 levers S^b and L^b to the normal positions, provided, however, that section Y—Z of track 1 is unoccupied. The holding circuit for relay P^b is the same as the pick-up circuit up to and including relay P^b, then through contact 90 76, wires 77 and 24 to battery B^b. Relay P^b, therefore, once picked up remains energized independent of the position of levers S^b and L^b, as long as track section Y—Z is unoccupied. It is now apparent that signal 95 B can be operated to its proceed position only by first throwing levers L^b and S^b to their normal positions to energize relay P^b, and then reversing signal lever S^b to close the signal circuit. The presence of a car 100 or train in section Y—Z, however, makes it impossible to effect or to retain the proceed indication of signal B.

For purposes of signaling from one tower to the other I provide communication circuits for operating the annunciators O^a and O^b and buzzers U^a and U^b. The circuit for signaling from tower T^a to tower T^b is as follows: from generator H^a, through wire 16, contact 30 of relay P^a, wire 31, push button 105 F^a, wire 32, contact segment a of traffic lever L^a normal, wire 33, buzzer U^a, wire 34, contact 35 of relay R^a, wire 36, contact 37 of relay R^a, wire 38, buzzer U^b, wire 39, contact segment a of traffic lever L^b normal, 110 wire 40, push button 41, wire 42, annunciator O^b, wires 43, 44 and 71 to generator H^a. This circuit is provided with a branch around contact segment a of lever L^b, which branch comprises contact segment b of lever L^b reversed, wire 47, push button F^b, and wire 47^a, so that this circuit is closed when the traffic lever L^b is in either its normal or its reversed position. The circuit for signaling from tower T^b to tower T^a is as follows: 115 from generator H^b, through wire 52, contact 45 of relay R^b, wire 46, push button F^b, wire 47, contact b of traffic lever L^b reversed, wires 48 and 39, buzzer U^b, wire 38, contact 37 of relay R^a, wire 36, contact 120 125 130

35 of relay R^d , wire 34, buzzer U^a , wire 33, contact segment a of lever L^a normal, wire 32, push button F^a , wire 49, annunciator O^a , wires 50, 44 and 51 to hand generator H^b .

5 The operation of the system is as follows:

When there is no car or train in the stretch of track between W and Z , the track relays R^a , R^d , R^e and R^b are energized, and signals D and E are in the proceed positions indicated in the drawing. If the traffic levers L^a and L^b and signal levers S^a and S^b are in their normal positions, relays P^a and P^b are energized, both their pick-up and holding circuits being closed. Relay Q is deenergized, its circuit being open at contact segment d of lever L^a . Motors M^a and M^b are also deenergized.

Under these conditions the operator at tower T^b may move the signal B to its proceed position to permit a train to pass through stretch $X-Y$ in the normal direction of traffic by simply reversing signal lever S^b , so that this lever closes at its contact segment b the circuit for signal B , as I have described hereinbefore. When a train accepts signal B and enters section $Y-Z$, it deenergizes track relay R^b . This relay opens at contact 28 the holding circuit of relay P^b , which in turn opens the circuit for signal B , causing it to display the stop indication. As the train enters section $V-Y$, it deenergizes relay R^e , which opens the circuit for signal E , so that this signal is brought to the stop indication. As the rear end of the train leaves section $Y-Z$, relay R^b is reenergized and closes at contact 28 the circuit for relay P^b . But this relay remains deenergized because its pick-up circuit is open at signal lever S^b . As the car or train proceeds into section $V-X$, it deenergizes relay R^d so that signal D changes to the stop position. As the rear end of the train leaves section $V-Y$, relay R^e again closes the circuit for signal E so that this signal is returned to the proceed position. As the train enters section $W-X$, it deenergizes relay R^a , causing this relay to break both the pick-up and the holding circuits of relay P^a so that the circuit for signal A cannot be closed until after the train has passed out of the section. To permit the passage of a second westbound train through stretch $W-X$ on track 1, the operator must first restore signal lever S^b to normal in order to pick up relay P^b . Then he can operate the signal B to its proceed position by again reversing signal lever S^b . Thus it is seen that when the traffic levers L^a and L^b are in the normal positions the operator at tower T^b is enabled to permit the passage of westbound trains over track 1 without coöperation of the man at tower T^a .

However, if the operator at tower T^a desires to send a train through stretch $X-Y$

over track 1 in the reverse direction, he can do so only with the coöperation of the operator at tower T^b . To notify the latter of this intention, the operator at tower T^a depresses push button F^a and turns hand generator H^b so that current is sent through the communication circuit hereinbefore traced, sounding buzzers U^a and U^b and operating annunciator O^b . It will be noted that this communication circuit is closed only if the track relays R^a , R^d , and R^e are energized; in other words, when track 1 is unoccupied between W and Y . If this circuit is closed, as indicated by the sounding of buzzer U^a , the operator at tower T^a turns lever L^a to the center position and waits for a release of the lever by the man at tower T^b . This operator, in response to buzzer U^b , restores the latch of annunciator O^b and reverses traffic lever L^b . He then depresses push button F^b and turns hand generator H^b , thus sending current through the circuit for motor M^a , which circuit was hereinbefore described. This current sounds buzzer U^a in tower T^a , notifying the operator that lever L^a is free to be turned to the reversed position. When the operator reverses lever L^a , relay Q is energized permitting signal A to be operated to the proceed indication by reversal of signal lever S^a .

When a car or train accepts signal A and enters upon track 1 via crossover C^a , it deenergizes relay R^a so that signal A changes to the stop indication. As the car or train proceeds over its route, it opens successively relays R^d , R^e and R^b which hold open the communication circuits between the towers and the energizing circuits for motors M^a and M^b until the car or train passes out of the corresponding sections. As explained hereinbefore, signal A can be restored to the proceed position only by first restoring both the traffic lever L^a and the signal lever S^a to their normal positions in order to pick up relay P^a . Once the traffic lever is in the normal position, it cannot be reversed until again unlocked by the operator at tower T^b . As explained hereinbefore, the communication and locking circuits between the towers are open until the car or train on track 1 has passed completely out of the stretch. It follows, therefore, that the operator at tower T^a must receive an unlock from the man at tower T^b for each train movement opposite to the direction of traffic.

On the other hand, if after the passage of an eastbound train over track 1, the operator at tower T^b desires to restore his traffic lever L^b to normal in order to send a train over this track in the normal direction, he signals to the operator at tower T^a by depressing push button F^b and cranking generator H^b . This current in flowing through the communication circuit traced

hereinbefore, sounds buzzers U^b and U^a and operates annunciator O^a . The operator at tower T^a gives the unlock by depressing push button F^a and turning generator H^a to sound buzzer U^b . The man at tower T^b then moves his traffic lever L^b to the center position so that motor M^b is energized to permit the operator to turn the lever L^b into the normal position. After movement of this lever to normal, the current from generator H^a flows through contact segment a of lever L^b and push button 41 to annunciator O^b . The man at tower T^b notifies the operator at the other tower that he has received the unlock by depressing push button 41 to interrupt the flow of the signaling current. The resultant break in the sounding of buzzer U^a is a signal to the operator at tower T^a that lever L^b is unlocked and restored to normal. The operator at tower T^b is now able to operate signal B to the proceed position by reversal of levers S^b as hereinbefore described.

Although I have herein shown and described only one form and arrangement of apparatus and circuits embodying my invention, it is understood that various changes and modifications may be made therein within the scope of the appended claims without departing from the spirit and scope of my invention.

Having thus described my invention what I claim is:

1. In combination, two stations, a communication circuit between said stations comprising a source of current at each station, and means at each station responsive thereto, a control device at each station comprising a lever having a normal and a reverse position, means for controlling said circuit by one of said levers so that said circuit is closed when said lever is in either position, and means for controlling the circuit by the other lever so that it is closed only when the lever is in the normal position.

2. In combination, a stretch of railway track, means for controlling railway traffic over said stretch in both directions comprising a lever adjacent each end of the stretch, each of said levers having a normal and a reverse position, a communication circuit comprising a source of current at each end of the stretch and means at each end of the stretch responsive thereto, means for controlling said circuit by the presence and absence of cars or trains in the stretch, means for controlling said circuit by one of said levers so that said circuit is closed when said lever is in either position, and means for controlling the circuit by the other lever so that it is closed only when the lever is in the normal position.

3. In combination, a stretch of railway track, means for controlling traffic over said stretch in both directions comprising a lever

adjacent each end of the stretch, each of said levers having a normal and a reverse position, a communication circuit extending throughout said stretch, track circuits for said stretch comprising relays for the control of said signal circuit, a hand generator at each end of the stretch for energizing the signal circuit, a buzzer and an annunciator at each end of the stretch responsive thereto, means for controlling said circuit by one of said levers so that the circuit is closed when said lever is in either position, and means for controlling said circuit by the other lever so that it is closed only when the lever is in the normal position.

4. In combination, a stretch of railway track, traffic controlling means for said stretch comprising a lever adjacent each end of the stretch each lever being capable of occupying two or more positions, locking means for each lever, a current generating means at each end of the stretch for energizing the locking means for the lever at the other end of the stretch to release such lever, means controlled by each lever for completing the connection of the corresponding locking means with the generating means at the opposite end of the stretch only when such lever occupies one position, and means controlled by each lever when in such position for rendering the adjacent generating means incapable of generating current.

5. In combination, a stretch of railway track, traffic controlling means for said stretch comprising a lever adjacent each end of the stretch each lever being capable of occupying two or more positions, locking means for each lever, a current generating means at each end of the stretch for energizing the locking means for the lever at the other end of the stretch to release such lever, each generating means comprising an armature, an exciting winding and a source of exciting current, means controlled by each lever for completing the connection of the corresponding locking means with the armature of the generating means at the other end of the stretch only when such lever occupies one position, and means controlled by each lever when in such position for disconnecting the source of exciting current from the exciting winding of the adjacent generating means.

6. In combination, a stretch of railway track, traffic controlling means comprising a lever adjacent each end of the stretch each lever having a normal, a center and a reverse position, locking means for each lever, a circuit for the control of each locking means and comprising a source of current at the opposite end of the stretch, track circuits for said stretch comprising track relays for the control of said circuit, means for each lever for closing the circuit for its locking means when the lever is in the center

position, means controlled by one lever for closing when in the normal position the locking circuit of the other lever, means controlled by the other lever for closing when in the reverse position the locking circuit for the first lever.

7. In combination, a stretch of railway track, traffic controlling means comprising a lever adjacent each end of the stretch, each lever having a normal, a center and a reverse position, locking means for each lever, a circuit for the control of each locking means and comprising a source of current at the opposite end of the stretch, track circuits for said stretch comprising track relays for the control of said circuit, means for each lever for closing the circuit for its locking means when the lever is in the center position, means controlled by one lever for closing when in the normal position the locking circuit of the other lever, means controlled by the other lever for closing when in reverse positions the locking circuit of the first lever, and means for each locking means controlled by the position of the corresponding lever for preventing the operation thereof by current from the adjacent source.

8. In combination, a stretch of track, traffic controlling means comprising a lever adjacent each end of the stretch each lever having a normal, a center and a reverse position, locking means for one lever for preventing movement thereof from normal to reverse position, locking means for the other lever for preventing movement thereof from reverse to normal position, a circuit for controlling both of said locking means, a hand generator at each end of the stretch for generating a distinctive current for said circuit for operating said locking means to release the levers, said locking means being responsive only to said distinctive current, means for each lever for closing the circuit of its locking means when in the center position, means controlled by one lever when in the normal position for closing the circuit for the locking means of the other lever, means controlled by the other lever when in the reverse position for closing the circuit for the first lever, and track circuits for said stretch comprising track relays for controlling said circuit.

9. In combination, a stretch of railway track comprising a section adjacent each end, track circuits therefor comprising track relays, a signal at each end of the stretch for governing traffic therethrough, a signal lever for the control of each signal, a traffic lever for the control of each signal lever, a relay adjacent each end of the stretch controlled by the track relay for the section adjacent said end and by the adjacent traffic and signal levers, means for controlling each end signal by the relay and the traffic

and signal levers adjacent its end of the stretch, a locking device for each traffic lever, a circuit for said locking devices controlled by the track relays for the stretch, and comprising a source of distinctive current at each end of the stretch, and means for controlling said circuit so that each locking device cannot be operated by current from the adjacent source.

10. A stretch of railway track, track circuits therefor comprising track relays, a railway signal for each end of the stretch, a signal lever for controlling each signal, a traffic lever for controlling each signal lever and having a normal, a center and a reverse position, locking means for controlling each traffic lever, a source of distinctive current and signaling means adjacent each end of the stretch, said signaling means and said locking means being responsive to said sources of current, a line wire parallel to the stretch of track and controlled by the said track relays, means adjacent one end of the stretch for connecting the adjacent source of current or the adjacent signaling means to one end of the line wire when the corresponding traffic lever is normal, and for connecting the adjacent locking device to said end of the wire when the traffic lever is in the center position and means adjacent the other end of the stretch for connecting the other source of current or the other signaling device to the other end of said line wire when said other traffic lever is in reverse position and for connecting the other locking device to said other end of the line wire when the said other traffic lever is in the center position.

11. In combination, a stretch of single track, two signals A and B for governing traffic into said stretch from opposite directions, two traffic levers L^a and L^b for said two signals A and B respectively, each lever having normal and reverse positions, means controlled by lever L^a and operable only when the lever is in reverse position for causing signal A to indicate proceed, means controlled by lever L^b and operable only when the lever is in normal position for causing signal B to indicate proceed, means for preventing lever L^a from being moved from normal to reverse position except when lever L^b is in reverse position, and means for preventing lever L^b from being moved from reverse to normal position except when lever L^a is in normal position.

12. In combination, a stretch of railway track, a traffic lever adjacent each end of the stretch each lever having a normal and a reverse position, means for preventing one lever from being moved from normal to reverse position except when the other lever is in reverse position, means for preventing the second lever from being moved from reverse to normal position except when the

first lever is in normal position, a signal controlled by the first lever and prevented from indicating proceed except when the lever is in reverse position, and a signal controlled by the second lever and prevented from indicating proceed except when the lever is in normal position.

13. In combination, a stretch of railway track, a traffic lever adjacent each end of the stretch each having a normal and a reverse position, means for preventing a complete movement of one lever from normal to reverse position except when such lever is in an intermediate position and the other lever is in reverse position, means for preventing a complete movement of the second lever from reverse to normal position except when such lever is in an intermediate position and the first lever is in normal position, a signal controlled by the first lever and prevented from indicating proceed except when the lever is in reverse position, and a signal controlled by the second lever and prevented from indicating proceed except when the lever is in normal position.

14. In combination, a stretch of railway track, a traffic lever adjacent each end of the stretch and each lever having a normal, an intermediate and a reverse position, means for locking one lever in intermediate position while moving from normal toward reverse position, means for locking the other lever in its intermediate position while moving from reverse toward normal position, means for releasing the first lever only when the second lever is in reverse position, means for releasing the second lever only when first lever is in normal position, a signal controlled by the first lever and prevented from indicating proceed except when the lever is in reverse position, and a signal controlled by the second lever and prevented from indicating proceed except when the lever is in normal position.

15. In combination, a stretch of railway track, a traffic lever adjacent each end of the stretch and each lever having a normal, an intermediate and a reverse position, means for locking one lever in intermediate position while moving from normal toward reverse position, means for locking the other lever in its intermediate position while moving from reverse toward normal position, means for releasing the first lever only when it is in its intermediate position and the second lever is in reverse position, means for releasing the second lever only when it is in its intermediate position and the first lever is in normal position, a signal controlled by the first lever and prevented from indicating proceed except when the lever is in reverse position, and a signal controlled by the second lever and prevented from indicating proceed except when the lever is in normal position.

16. In combination, a stretch of railway track, a traffic lever adjacent each end of the stretch and each lever having a normal, an intermediate and a reverse position, means for locking one lever in intermediate position while moving from normal toward reverse position, means for locking the other lever in its intermediate position while moving from reverse toward normal position, an electrically operated releasing device for each locking means adapted when energized to release the locking means, a line wire extending between said levers, a source of current adjacent each lever, means for each lever arranged to connect the adjacent end of said line wire with the corresponding releasing device when the lever is in the intermediate position but not when the lever is in normal or reverse position, means for one lever for connecting the adjacent end of said line wire with the adjacent source of current when such lever is in normal position only, means for the other lever for connecting the adjacent end of said line wire with the adjacent source of current when such lever is in reverse position only, and signals for said stretch controlled by said levers.

17. In combination, a stretch of railway track comprising a track circuited section, a traffic lever capable of a normal and a reverse position, a signal lever capable of a normal and a reverse position, a relay, means for energizing said relay only when the track circuited section is unoccupied and both of said levers are in normal position, means for maintaining said relay energized irrespective of the position of said levers provided said track circuited section is unoccupied, a second relay, means for energizing said second relay only when said first relay is energized and said traffic lever is in reverse position, and a signal controlled by said second relay and signal lever and prevented from indicating proceed except when said second relay is energized and said signal lever is in reverse position.

18. In combination, a stretch of railway track comprising a track circuited section, a traffic lever capable of a normal and a reverse position, a signal lever capable of a normal and a reverse position, a relay, means for energizing said relay only when the track circuited section is unoccupied and both of said levers are in normal position, means for maintaining said relay energized irrespective of the position of said signal lever provided the track circuited section is unoccupied and the traffic lever is in normal position, and a signal controlled by said relay and signal lever and prevented from indicating proceed except when said relay is energized and said signal lever is in reverse position.

19. In combination, a stretch of railway track comprising a track circuited section, a traffic lever capable of a normal and a reverse position, a signal lever capable of a normal and a reverse position, a relay, means for energizing said relay only when the track circuited section is unoccupied and both of said levers are in normal position, means for maintaining said relay energized irrespective of the position of said levers provided said

track circuited section is unoccupied, and a signal controlled by said relay and levers and prevented from indicating proceed except when said relay is energized and both 15 of said levers are in reverse positions.

In testimony whereof I affix my signature in presence of two witnesses.

CHARLES STEPHENS.

Witnesses:

H. E. JOHNSON,
GEO. J. HOOPER.
